Attorney

UNITED STATES PATENT OFFICE.

ALLAN W. ALEXANDER, OF PITTSSTON, PENNSYLVANIA.

BOOK HANGER AND PROTECTOR.

Application filed March 17, 1922. Serial No. 544,562.

To all whom it may concern:

Be it known that I, ALLAN W. ALEXANDER, a citizen of the United States of America, residing at Pittston, in the county of 5 Luzerne and State of Pennsylvania, have invented certain new and useful Improvements in Book Hangers and Protectors, of which the following is a specification, reference being had therein to the accompanying 10 drawings.

This invention relates to a book hanger and protector and it has for its object to provide an improved device of this character by means of which books such as catalogues, telephone directories and the like may be hung upon a nail or other support. It is a further object of the invention to provide a hanger of the character described constructed in such manner as to prevent 15 the marring of desks or other polished articles of furniture if the book by which the hanger is carried is drawn thereacross or laid thereon. It is a further object of the invention to provide a hanger of the character described including elements adapted 20 to bear advertising matter.

Further objects and advantages of the invention will be set forth in the detailed description which follows.

30 In the accompanying drawing:

Fig. 1 is a side elevation of a portion of a book having the hanger of the invention applied thereto;

Fig. 2 is a perspective view of the elements constituting the hanger; and

Fig. 3 is a transverse sectional view through a book having the hanger applied thereto.

Like numerals designate corresponding 40 parts in all of the figures of the drawing.

It is a well known fact that telephone directories, as delivered to subscribers, are perforated transversely near their upper rear corner. However, the telephone companies do not supply any suspending elements for these books. The subscriber is free to use any suspending element that he sees fit. Some subscribers use pieces of string, others use pieces of wire. The 45 strings are limp and become twisted so that it is a tedious matter to straighten them out and engage them with a nail or other support upon which the directory is to be hung.

The wires, upon the other hand, scratch the 50 surfaces of highly polished desks and other

articles of office furniture and are objectionable for that reason.

In carrying out the invention I provide a loop of wire 5 which is adapted to lie substantially centrally of the book. No part 60 of this wire is disposed upon the outside surface of the book. The inner ends of the wire are bent in opposite directions, as indicated at 6, and terminate in loops at 7 which are engaged by eyes 8 of buttons 9. These 65 buttons are preferably provided with perfectly smooth celluloid outer faces which will not mar the surface of highly polished articles of furniture. The eyes 9 are preferably formed by suitably bending wires 10 70 which extend transversely across the backs of the buttons and are provided with ends 11 which are engaged beneath the overturned edges of the said buttons.

The surfaces of the buttons may be utilized 75 to bear advertising matter, such as is indicated at 12.

In applying the device, the book to be supported, which is indicated at 13, is opened substantially at the center and one 80 end of the loop 5 is passed through the perforated part 14 formed in those leaves which lie to one side of the center. The eye 8 of a button 9 is then engaged with the loop 7, said button lying outside of the book. The 85 other end of the loop 5 is then forced through the perforated part 14 of those leaves which lie upon the other side of the center and the other button is in like manner attached to the extremity of said wire, 90 the book is then closed and the parts lie in the position illustrated in Fig. 3. Another way which might be resorted to in the application of the device is to first attach the button 9 to loop 7 and then pass the loop 6 95 constituting the other or free end of the wire through the perforation 14 from side to side of the book and then attach the other button 9 to said loop 6. Thereafter, by opening the book in the middle the intermediate portion of the wire may be grasped and drawn upwardly to form the loop 5.

The loop 5 may be formed of any suitable material but I preferably make it of spring steel wire so that it will retain its 105 open loop formation thus rendering it easy to engage it with a nail, hook or like support. Furthermore, this spring steel wire enables me to make the loops 7 in the form of snap loops. In other words, by making 110

the terminal ends of these loops lie very close to the adjacent part of the loop 5, the eyes 8 are caused to snap through the restricted openings thus provided. Consequently the buttons will not easily become disengaged from the loops 7.

From the foregoing description it will be seen that simple and efficient means are herein provided for carrying out the object 10 of the invention. However it is to be understood that the invention is not limited to the precise construction set forth but that it includes within its purview whatever changes fairly come within either the terms 15 or the spirit of the appended claims.

Having described my invention what I claim is:

1. A device of the character described comprising a loop having its ends outturned 20 in opposite directions to pass through the perforated portions of a book to be suspended, buttons adapted to lie outwardly of the covers of the book and means for engaging said buttons with said ends.
- 25 2. A device of the character described comprising in combination a looped element,

oppositely projecting aligned ends carried thereby which lie at substantially right angles to the looped element to thereby constitute a structure of substantially inverted 30 T shape, the looped element being adapted to lie substantially centrally within a book and the aligned ends being adapted to project in opposite directions through perforated portions of such book and retaining 35 means at the terminals of the aligned ends for preventing inward movement of such ends.

3. A device of the character described comprising a wire loop having its inner ends 40 outturned in opposite directions to pass through the perforated portions of a book to be suspended and having its terminal ends bent to looped formation, substantially 45 flat buttons adapted to lie outwardly of the covers of the book and eyes upon the rear faces of said buttons adapted to engage with the loop terminals of the wire loops.

In testimony whereof I hereunto affix my signature.

ALLAN W. ALEXANDER.
